United States Patent Office

Des. 219,772
Patented Jan. 26, 1971

219,772

FOOD STAND

John D. Lenzi, 662 Payne Ave.,
St. Paul, Minn. 55106

Filed Nov. 3, 1969, Ser. No. 19,909

Term of patent 14 years

Int. Cl. D25—04

U.S. Cl. D13—1

FIG. 1

FIG. 2

FIG. 3

FIG. 4

FIG. 5

FIG. 1 is the front elevation of the food stand of my invention;

FIG. 2 is the left side elevation thereof;

FIG. 3 is the top plan view thereof;

FIG. 4 is the rear elevation thereof; and

FIG. 5 is the right side elevation thereof.

I claim:

The ornamental design for a food stand, substantially as shown and described.
